(57) **CLAIM**

The ornamental design for a front combination lamp for automobile as shown and described.

DESCRIPTION

FIG. 1 is a front and right perspective view of a front combination lamp for automobile showing my new design; FIG. 2 is a rear and right perspective view thereof; FIG. 3 is a right side elevation view thereof; FIG. 4 is a left side elevation view thereof; FIG. 5 is a front elevation view thereof; FIG. 6 is a rear elevation view thereof; and, FIG. 7 is a top plan view thereof.

The claimed design is indicated by the relatively dark portions in the figures, while the relatively light and de-emphasized portions form no part of the claimed design.
